Primary Examiner — Eric L Goodman*Assistant Examiner* — Sanjeev Paul(74) *Attorney, Agent, or Firm* — Sterne, Kessler, Goldstein & Fox P.L.L.C.(57) **CLAIM**

The ornamental design for a set of eyeglass components, as shown and described.

DESCRIPTION

FIG. 1 is a front perspective view of a set of eyeglass components showing the new design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.

The broken lines in the Figures show portions of the set of eyeglass components that form no part of the claimed design.

1 Claim, 4 Drawing Sheets(56)
